UNITED STATES PATENT OFFICE.

JOHN M. ETIMAN, OF MAPLETON, NORTH DAKOTA.

CAR-DOOR.

1,125,826.

Specification of Letters Patent.

Patented Jan. 19, 1915.

Application filed September 13, 1911. Serial No. 649,090.

To all whom it may concern:

Be it known that I, JOHN M. ETIMAN, a citizen of the United States of America, residing at Mapleton, in the county of Cass 5 and State of North Dakota, have invented new and useful Improvements in Car-Doors, of which the following is a specification.

The invention relates to improvements in car doors, and more particularly to doors 10 of that type used in connection with cars for hauling grain or material of a like nature.

One object of the present invention is to provide a door of this character which 15 shall be made of upper and lower sections and adapted to be held against the roof of a car and out of the door opening when desired.

Another object of the invention is to provide 20 a car door in which the sections may be pivotally connected to the sides of the door opening for swinging movement; the connection being provided with means whereby the door may be detached therefrom for the purpose of adapting the car to various kinds of material.

A further object of this invention is to provide 25 a supplemental door for use in conjunction with the main door and positioned 30 below the main door whereby coal and other heavy materials may be discharged or shoveled from the bottom of the car without displacing the main door.

With the above and other objects in view, 35 which shall appear as the description progresses, the invention consists in the construction, combination and arrangement of parts hereinafter fully described and falling within the scope of the appended claims.

In the drawings forming a portion of this specification, Figure 1 is a side elevation 40 of a car door constructed in accordance with the present invention, looking from the inside of the car, the roof and floor of the car being shown in sections. Fig. 2 is a horizontal sectional view on the line 2—2 of Fig. 1. Fig. 3 is a vertical section on the line 3—3 of Fig. 1. Fig. 4 is a detail perspective view of one of the supports for the lower section of the door. Fig. 5 is a detail perspective view of one of the guide members carried by the lower section of the door, and Fig. 6 is a top plan view of the

supplemental door showing the same in open position. 55

Similar reference characters designate like parts throughout the several views.

Referring more particularly to the accompanying drawings, the numeral 1 designates the roof of the car, 2 the floor, and 3 60 the side of the car provided with a door opening 4.

At each side of the door opening 4, the side 3 of the car is provided with door posts 5 arranged interiorly of the car and 65 extending, preferably, the full height thereof. The door posts 5 adjacent the opening 4 are formed with rabbeted or cut away portions 6 which extend from a point adjacent the bottom of the posts to the top of 70 the same.

The door, in the present instance comprises upper and lower sections 7 and 8. On its rear surface the lower section 8 of the door is provided with lugs 9, which 75 latter are perforated transverse their length and are arranged adjacent the opposite side edges of the said section. Pivotally secured to the outer edge of the door posts 5 and above the sections 7 and 8, are a pair 80 of supporting members designated by the letter B. The supporting members B are made of metal or any other suitable material and are identically constructed, and each comprise a main bar 10 to the lower 85 end of which is pivotally connected a latch member C, which latter includes a retaining strip 11 provided with a transverse opening and pivoted upon one side of the bar 10. Arranged within the opening in 90 the retaining strip 11 is a locking pin 12 formed with a transverse opening 13.

Pivoted to the opposite side of the bar 10 and in parallel relation with the retaining strip 11 is a locking strip 14, the lower end 95 of which is cut away as at 15 for the purpose of receiving the locking pin 12. The rear wall of the cut away portion 15 is provided with a key 16 designed to enter the opening 13 in the pin 12 whereby to lock 100 the supporting member B to the lower section of the door. From this construction it will be seen that the pin 12 carried by the retaining strip 11 is passed through the opening in the lug 9 after which the locking 105 strip 14 is swung on its pivot and into en-

gagement with the pin 12 thereby locking the section 8 to the supporting member B so that the said section may be supported within the door opening 4.

5 At its opposite vertical side edges the lower section 8 of the door is provided with 10 bindings C', each of which comprises a base plate 17 and a retaining plate 18. The plate 17 has one end secured to the outer 15 surface of the section 8 of the door and projects laterally therebeyond, the projecting portion terminating in a keeper 19. The plate 18 is of substantially Z-shape and has a long arm 20 designed to engage the keeper 19 in the plate 17. The shorter arm of the Z-shaped plate 18 terminates in alinement with the secured end of the plate 17 and is provided with an opening alining with an opening in the plate 17, both of said openings being designed to receive a bolt 21 whereby the bindings C' may be secured to the edges of the section 8 of the door. These 20 bindings C' are designed for engagement with the rabbeted portion 6 of the door posts 5 and are held therein by means of 25 sliding plates 22 arranged upon the inner side of the posts 5 and slideable upon bolts 23. The plates 22 are provided with slots 24 having horizontal portions 25 terminating in upwardly inclined portions 26 whereby upon the release of the plates 22 the same may gravitate to their closing positions upon the bolts 23 due to the inclined portion 26 of the slot 24 thereby securely holding 30 the section 8 of the door A in closed position. The upper section 7 of the door A has its lower longitudinal edge offset to provide a flange 27 designed to engage the inner surface of the section 8 of the door, 35 the offset portion serving to support the section 7 upon the section 8. Adjacent its upper edge the section 7 is provided upon its inner surface with eyes 28, each of which is designed to receive one end of one of a 40 pair of supporting rods 29. One end of the rods 29 is pivotally secured to the door lintel above the pivotal connection of the member B and these rods are provided at their opposite ends with hooked terminals 30 which latter pass through the eyes 28 of the section 7 and are removable therefrom.

The lower section 8 of the door A is provided with an outlet opening 31 controlled by a sliding door 32 whereby the grain or other material may be discharged from the car as is obvious.

From the foregoing it will be seen that the upper section 7 of the door may be swung inwardly and connected, by any suitable means, to the inner wall of the roof 1 of the car, after the corn or other material, contained within the car, has been discharged through the openings 31. After the door section 7 has been removed from the opening 4, the plates 22 may be moved to

uncover the rabbeted portions 6 of the door posts 5, and the section 8 of the door swung upwardly against the roof of the car and supported thereby in any suitable manner whereby access may be had to the lower part 70 of the car.

Mounted upon the floor 2 of the car at the bottom of the door opening 4 is a supplemental door D, the upper edge of which engages the lower edge of the section 8 of the door A. The door posts 5 at their lower ends are provided with spaced cleats 33 between which is mounted the door D. The supplemental door D comprises two relatively movable sections 34 and 35 hinged 80 connected at 36. The section 35 is of less length than the section 34 and has rigidly secured to its upper face an extension 37 designed to overlap the section 34 and provided with an opening through which 85 passes a staple 38. The free end of the section 34 is provided upon its front face with an enlargement 39 designed to lie flush with the section 37 in the closed position of the door and provided with a hasp 90 40 adapted to engage the staple 38 whereby the door may be locked in its closed position. At its ends, the supplemental door D is provided with substantially U-shaped wear plates 41 which latter embrace the 95 ends of the supplemental door and are designed to be inserted between the cleats 33 upon the door posts 5. This supplemental door D is more particularly designed for use when the car is carrying coal or other 100 heavy materials so that the said material may be shoveled or taken from the bottom of the car thereby obviating the labor incident to shoveling out the contents above the section 7 of the door A. From this 105 construction it will be seen that upon disengaging the hasp from the staple, the section 34 will be forced outwardly by the pressure of the material within the car, and the section 35 inwardly whereby the supplemental door will be removed from the door opening.

Having thus described my invention, what I claim and desire to secure by Letters-Patent is:

1. The combination with a car having a door opening therein, and door posts mounted adjacent said door opening, of a door section, supporting members pivotally secured to the door posts, latch members 120 carried by said supporting members and adapted to engage the door section to support the same within the door opening, each of said latch members including a retaining strip, a locking pin carried by said strip, and a locking strip movable relatively to the retaining strip and adapted to engage the locking pin to hold the supporting members to the door section.

2. The combination with a car having a 130

door opening therein, of a door section mounted for swinging movement within the door opening, bindings secured to the opposite vertical edges of the section and comprising a base plate extended beyond the respective edge of the door and bent upon itself to provide a keeper, and a retaining plate secured to the side of the door opposite from the base plate and extended beyond the ad-

jacent edge of the base plate and of substantially Z-shape and having the free edge thereof in engagement with the keeper.

In testimony whereof I affix my signature in presence of two witnesses.

JOHN M. ETIMAN.
